UNITED STATES PATENT OFFICE.

HENRY M. HOWARD, OF BROOKLYN, ASSIGNOR TO JOHN STEPHENSON, OF NEW YORK, N. Y.

IMPROVEMENT IN WINDLASSES AND CRANKS FOR BRAKES.

Specification forming part of Letters Patent No. 146,182, dated January 6, 1874; application filed June 28, 1873.

To all whom it may concern:

Be it known that I, HENRY M. HOWARD, of Brooklyn, in the county of Kings and State of New York, have invented a new and useful Improvement in Windlass and Crank for Horse-Car Brakes, of which the following is a specification:

The object of this invention is to give the drivers of horse-cars more complete control over the brake thereof than they now have; and consists in a swiveled and adjustable crank or handle, attached to the windlass so as to operate as hereinafter described.

In the accompanying drawing, Figure 1 represents a side elevation. Fig. 2 is a horizontal section of Fig. 1 taken on the line *x x*.

Similar letters of reference indicate corresponding parts.

A is the windlass, around the lower end of which the brake-chain is wound when the windlass is revolved. B is the crank. Ordinarily the crank and the windlass are in one piece, the upper end of the latter being drawn out to the proper size and shape and bent over in the crank form, and the windlass is made round. By my improvement the windlass is made polygonal, preferably a hexagon, with the upper end reduced in size with a loose collar or swivel, C, placed thereon, which is kept in position by the screw-nut D. The crank has two pairs of jaws, E and F. The former is made to fit two opposite sides of the windlass, and the latter are attached, by swivel-pins G, to the loose collar or swivel C, as represented in the drawing.

It will be seen that, by raising the outer end of the crank, the jaws E will be detached from the windlass, and the crank may be turned round to allow the jaws E to engage with any other two of the sides of the windlass. By this means the driver is enabled to take a hold of the windlass that will allow him to exert the required strength to the best advantage.

When the common brake is released the reaction causes the crank to revolve sometimes with great rapidity, and much danger to passengers. This danger, with my crank, is avoided. It is only necessary to raise it so that the jaws E will be detached from the windlass, when

the latter will revolve without revolving the crank.

When the brake is not in use, as, for instance, when the car is reversed, the crank may be thrown over so as to hang out of the way, as seen in dotted lines in Fig. 1.

The horse-car brake is usually operated by the driver. The driver rotates a crank, and the crank is rigidly connected with the reel-shaft or windlass. In order that the driver may exert his power to the best advantage, the crank-handle should be at a desirable location in its orbit. This is impossible in the ordinary construction, because, though the brake at the outset may be so adjusted as to bring the handle to the right position, it will not so continue, for, as the clogs or brakeshoes wear away by contact with the wheels, the crank-handle changes position, and consequently the efficiency of the driver for stopping the car is diminished, and jeopardy results. Another evil inherent in the fixed crank is its release from the driver's hand while in a state of recoil, and thus violently striking passengers on a crowded platform produces serious injury.

Both of the foregoing evils are remedied by the jointed-brake reel-crank, as herein specified, because the driver can, at will, change the crank-handle to any desirable position in its orbit, and can also release the reel and recoil the brake without rotating the crank.

To attain these desirable results the following construction is made: The brake-work, from the crank to the wheels of the car, may be of any of the known methods of construction. The reel-shaft, above the upper reel-holder, becomes a polygon, with a journal in proximity to the polygon. On the journal is placed a collar of special form, properly secured in position. The reel crank or handle is made with a socket corresponding in form, and adapted to receive the upper end of the reel-shaft. One side of the crank-socket is made open, so that the reel-shaft may slip in or out at that open side. The socket is also made with a recess proper to admit the collar before referred to. When the reel-shaft, with the collar, is in the socket of the crank, as described, a bolt or pin is passed through the

cheeks or sides of the crank-socket and through the collar in such a manner as not to interfere with the reel-shaft journal. The union of reel and crank may be by a ball-and-socket joint. The reel-shaft and the crank are thus united, so that the handle of the crank may be elevated and the polygon part of the reel released from the crank-socket. While the reel-shaft is thus released, it has freedom to revolve on its axis without rotating the crank.

I am aware of a patent issued to Stephen L. Avery for a well-brake or hoisting apparatus, in which the crank is in the same plane as the ratchet-wheel on the horizontal shaft. It has also a slight freedom of motion, and is made to act as a brake by pressure on the side of the ratchet-wheel for the purpose of retarding the descent of the bucket, &c.; but the

mechanical device and the design are entirely different, and therefore disclaimer is here made for such thing or purpose.

What I claim is—

1. The brake-reel approaching the upper end, made of polygonal form, with a journal in proximity to such form.
2. The combination of the reel-shaft with loose collar on the journal.
3. The combination of the reel-shaft with the collar, secured in the crank-socket by bolt, or pin, or journal, or ball and socket.
4. The reel-crank, made with the socket open at the side to permit the exit of the reel.

HENRY M. HOWARD.
